UNITED STATES PATENT OFFICE.

DUGALD C. JACKSON AND CONRAD M. CONRADSON, OF MADISON,
WISCONSIN.

DESIGN FOR A FRAME FOR ELECTRIC MOTORS, &c.

SPECIFICATION forming part of Design No. 25,033, dated December 31, 1895.

Application filed July 26, 1895. Serial No. 557,244. Term of patent 7 years.

To all whom it may concern:

Be it known that we, DUGALD C. JACKSON and CONRAD M. CONRADSON, citizens of the United States, residing at Madison, in the county of Dane and State of Wisconsin, have invented a certain new and original Design for the Frames of Electric Motors and Generators, of which the following is a specification.

Our invention has reference to a novel design for the frames of electric motors and generators.

In the drawings, Figure 1 is an end elevation of our motor-frame, and Fig. 2 a front face view of the same.

A indicates the main body of the frame. 15
On the front flat face of the part is the open or skeleton bracket or bonnet B, while on the rear face is the closed bracket or bonnet C.

Having described our invention, we claim—
The design for a frame for an electric motor, shown and described.

In witness whereof we hereunto set our hands in the presence of two witnesses.

DUGALD C. JACKSON.
CONRAD M. CONRADSON.
